CLAIM

The ornamental design for a disposal container for hypodermic needles, substantially as shown and described.

DESCRIPTION

FIG. 1 is a front perspective view of a disposal container for hypodermic needles embodying my design;
FIG. 2 is a front view thereof;
FIG. 3 is a left side view thereof;
FIG. 4 is a right side view thereof;
FIG. 5 is a back view showing the side opposite that shown in FIG. 1;
FIG. 6 is a top plan view thereof;
FIG. 7 is a bottom plan view thereof;
FIG. 8 is a sectional view taken on line 8—8 of FIG. 1;
FIG. 9 is a sectional view taken on line 9—9 of FIG. 1;
FIG. 10 is a sectional view taken on line 10—10 of FIG. 1.
